DISPLAY CONTAINER

Filed Sept. 8, 1930

UNITED STATES PATENT OFFICE

OTTO Y. SCHNERING, OF CHICAGO, ILLINOIS, ASSIGNOR TO CURTISS CANDY COMPANY,
OF CHICAGO, ILLINOIS, A CORPORATION OF ILLINOIS

DISPLAY CONTAINER

Application filed September 8, 1930. Serial No. 480,315.

The present invention has to do with a packing and display container or box and relates particularly to the arrangement and structure of parts whereby two types of merchandise may be displayed in a single carton, one kind of merchandise being used to maintain the other in an orderly condition. The objects of the invention include, among others, a novel display package, an improved device for the display of different types of merchandise in a single packing container, an unique package for confections of different characteristics, and a novel arrangement for a merchandising container.

These objects, and such other objects as may hereinafter appear, are obtained by the novel construction, unique arrangement, and improved combination of the several elements which go to make up the device disclosed in the accompanying drawing, hereby made a part of this specification, and in which:

Figure 1 is a perspective view of a container embodying the invention herein described, the said container being filled with merchandise; Figure 2 is a plan view of the blank for an insert which is used in connection with the box or display bottom; Figure 3 is a plan view of a blank which is superimposed upon the blank shown in Figure 2; Figure 4 is a transverse section on the line 4—4 of Figure 1; Figure 5 is a longitudinal section of the line 5—5 of Figure 1; Figure 6 is a plan view of a blank for a temporary end support used for the centrally disposed merchandise in the container; and Fig. 7 is a plan view of the display card.

Like reference characters are used to designate similar parts in the drawing and in the description of the invention which follows. For convenience the invention will be described generally in the order of the assembly of the container and the merchandise.

The bottom of the package comprises a telescoping member or section 10 having upright sides and ends 11. Such member is a conventional shallow telescoping box mem-

ber. Into this member, there telescopes one member later to be described and thereover, there telescopes a cover 12 which has ends and sides 13 which overlay the ends and sides 11 of the bottom 10. The top 12 is of a conventional telescoping characteristic and is removed when the candy and remainder of the box is placed on display, thereafter seldom to be replaced about the package.

Within the member 10 is a filler or spacer 15 member formed from the blank 15. Said blank 15 has a central section 16 extending from end to end and around which there are flaps or wings 17. There are scores 18 intermediate the section 16 and the wings 17 to facilitate the folding of the wing 17 in a position normal to the section 16. Wings 17 in the assembled box depend into the bottom 10 parallel to the ends and sides 11 thereof, the section 16 being thus held elevated from the bottom of box 10 and generally substantially level with the top edges of the ends and sides 11. It is preferred that the section 16, so held, should be in a horizontal plane slightly below rather than slightly above the level of the top edges of the ends and sides 16.

Reference should now be had to Figure 2. In the present form of the invention there are four apertures formed therein. These apertures are obtained by die-cutting or by otherwise removing adjacent the longer score lines 18 four sections of material. A plurality of teeth or serrations 19 are thus formed adjacent to the side wings 17. One end of such die-cut apertures may coincide with the end scores 18.

The opposite side of each of said apertures is formed by a combination of die-cutting and scoring. There is formed by such die-cutting and scoring a U-shaped member 22 the ends of which are separated from the material of center section 16 by die cuts 23 which extend to the straight bottom edge of said U-shaped member 22, which edge is separated from the member 16 by a straight line scoring 24 which connects the two die cuts 23. One of said die cuts may coincide with score 18 between member 16 and ends 17. Thus the U-shaped member 22 may be articulated downwardly and arranged paral-

lel to the sides 17. The magnitude of the member 22 is such that it exactly coincides with the height of the sides 17 and has an under straight edge parallel to the top surface of member 10.

5 A bridge of material 25 is left between each of the four apertures in member 16. Said apertures at one side of the sheet 16 are parallel with the other two apertures at the 10 other side thereof but are reversed in respect thereto.

The member 15, in the form described, i. e., with wings 17 and tabs 22 folded downwardly, is adapted to be inserted into the member 15 10 with the wings 17 and the wings 22 in parallelism. The member 15 is thus provided with edge and center support and will not cave in under the normal weight of confec- 20 tions displayed thereon.

20 Over the central portion of blank 15, i. e., section 16, there is disposed a generally rectangular member 30 of sheet material which has parallel straight end edges 31, and side edges 32, each having aligned series of serrations. At the center of the member 30 and between aligned series of serrations 32, there are extensions 33 which terminate in blunt ends, which extensions 33 register with a portion of the bridges 25. Between the extensions 33 and the end edges 31, the serrations 32 are complementary to and correspond and register with the serrations 19 on the margin of the section 16. The member 30 normally is assembled with member 15 without adhesive but, of course, can be adhesively applied thereto, when desired. Between serrations 19 and 32, there is a space to receive merchandise, later to be described.

At the end of the device, there may be supplied 40 a display card 35 which has a section 36 articulated for seating beneath the member 15 and to rest upon the bottom member 10. Next above the section 36 is a section 37 which in the assembled package remains upright at all times. Depending therefrom is a section 38 upon which there may be advertising matter. Said section 38 is folded over the merchandise in the container, now to be described and is held down by the cover 12 50 while the package is not in use, but which section 38 stands upright when the goods are on display or are on sale. Any suitable form of articulation may separate the sections 36 and 37 and the sections 37 and 38.

55 Between the serrations 32 on the member 30 and the marginal serrations 19 in the member 16, ordinarily two cylindrical packages 40 of merchandise are placed, there being four serrated compartments in the present 60 instance for five double rows of such merchandise. Such merchandise packages 40 have a portion of the periphery of the outside members thereof situated within the curved portion of the marginal serrations 65 19, the points of such serrations 19 separat-

ing adjacent packages. A similar row of packages is arranged with the teeth 32 separating packages one from another, while the curved body portions of the merchandise packages are disposed intermediate such 70 teeth 32.

In the present instance forty packages of cylindrical merchandise may be safely disposed in the device, and are held upright therein by the toothed members 19 and 32 75 just described. Intermediate the members 40 held upright by the means described, there is a platform, which platform has as its top member the toothed rectangular element 30.

Upon said spacer element 30 there may now 80 be disposed merchandise possessing in its finished form a parallelepiped configuration such as packages 41 shown in the drawing. Such merchandise may extend the full length of the said member 30 which is bounded at 85 the back by the display card 35, and at the front by a removable member 50.

When the package is on display, no support is required at the other end of the package, thus leaving exposed to view a merchandise display comprising at each side two rows of cylindrical pieces 40 of merchandise, the top end of which does not reach to the top layer of the parallelepiped packages 41 disposed therebetween. The advertising material on the cylindrical package 40 is preferably upon the upper half thereof, so that such material is plainly visible to a prospective purchaser. The cylindrical merchandise packages 40 do not materially interfere with 100 full vision of the parallelepiped packages 41 disposed therebetween, so that in the display package described there is an arrangement of merchandise of two entirely different characteristics which attracts the eye of the prospective purchaser, the display of one portion of the merchandise not interfering with full vision of the other, but accentuating it, although one part of the merchandise is adapted to provide a support for the other 110 part of the merchandise.

During packing, it is usual and customary to supply at the center of the package the temporary packing element 50, in the present instance comprising a sheet of paste-board or the like having extensions 51 projecting therefrom. This element could be a truly rectangular sheet, but experience teaches that if the sheet has a V-shaped opening between the extensions 44 the retailer will 105 quickly understand that it is to be removed as soon as possible. If the merchant does not understand that the member 50 may be removed, the V-shaped opening between the extensions 51 permits of a substantially complete visualization of the merchandise 115 41 adjacent thereto and permits of such merchandise being readily removed without any danger of having the display thereof upset by a careless clerk or self-serving individual. 120

The central packages 41 are removed in any desired order as they are sold. The removal of one package at a time does not in any way disturb the general appearance of the central 5 display. If such central display loses its orderliness, it is a simple matter to rearrange the packages 41.

The cylindrical packages 40 may be removed in any order. The removal of a member 10 does not totally destroy the effectiveness of the member paired therewith to support the merchandise. The size of the opening in which the two cylinders 40 are disposed is such that even if one cylinder is removed and 15 the other is knocked over, the knocked over member will not fall flat, but on the contrary will remain substantially upright. If it inclines outwardly, the bottom end rests against the wing 22 with the body portion against 20 a marginal serration 19 of the member 16. Should a member 40 incline inwardly, the body thereof will rest against the adjacent packages 41. Thus the cylindrical merchandise 25 40 is maintained in upright or substantially upright position at all times.

The device has the advantage of combining highly efficient packaging for two types of merchandise plus an attractive display for such merchandise when the package is 20 opened. It is in condition for immediate disposition upon a counter, showcase, or shelf without unpacking or repacking.

I claim:

1. A box for merchandise articles of different characteristics, comprising a bottom, a merchandise-supporting member telescoping into said bottom, said supporting member having a plurality of spaced apart openings therein in parallelism, one side of said 40 openings being serrated to provide dividers between items of merchandise, a top for said supporting member, and a display card at one end of said box between said bottom and supporting member and forming an end support for merchandise on said top.

2. A box for merchandise articles of different characteristics, comprising a bottom, a merchandise supporting member telescoping into said bottom, said supporting member having a plurality of spaced apart openings therein in parallelism, a top for said supporting member, a display card at one end of said box between said bottom and supporting member and forming an end support for merchandise on said top, and a second card at the other end of said box to provide a merchandise support opposite said display card.

3. A box for merchandise articles of different characteristics, comprising a bottom, a merchandise supporting member telescoping into said bottom, said supporting member having a plurality of spaced apart openings therein in parallelism, one side of said openings being serrated to provide dividers between items of merchandise, a top for said

supporting member, said top having serrations registering with and complementary to the serrations in said supporting member, a display card at one end of said box between said bottom and supporting member and forming an end support for merchandise on said top, and a second card at the other end of said box to provide a merchandise support opposite said display card.

4. A box for merchandise articles of different characteristics, comprising a bottom, a merchandise supporting member telescoping into said bottom, said supporting member having a plurality of spaced apart openings therein in parallelism, the material removed from said supporting member to form said openings being articulated normal to said supporting member to rest upon said bottom, a top for said supporting member, and a display card at one end of said box between said bottom and supporting member and forming an end support for merchandise on said top.

5. A box for merchandise articles of different characteristics, comprising a bottom, a merchandise supporting member telescoping into said bottom, said supporting member having a plurality of spaced apart openings therein in parallelism, one side of said openings being serrated to provide dividers between items of merchandise, a top for said supporting member, said top having serrations registering with and complementary to the serrations in said supporting member and extending beyond the contiguous edges of the openings in said supporting member, a display card at one end of said box between said bottom and supporting member and forming an end support for merchandise on said top, and a second card at the other end of said box to provide a merchandise support opposite said display card.
